VANITY CASE CONSTRUCTION

Fred Spitalny, Elizabeth, N. J.

Application November 15, 1935, Serial No. 49,881

3 Claims. (Cl. 220—55)

This invention relates to improvements in vanity cases and the like, and more particularly to improved opening and closing latch means therefor.

5 The invention has for its major object the provision of a vanity case having improved latch means for expeditiously opening and closing the hinged portions comprising said case.

More specifically, the invention contemplates 10 the provision of a vanity case comprising at least two hinged portions, one of said portions being provided with a member of the approximate length of the case to serve as a closure fastener whereby tilting said member will free the other portion of said case for ready and easy access to the interior of said case.

A further object is to provide a unique and convenient latch member for a vanity case.

The foregoing and many other features and 20 advantages of the invention will be more readily apparent from the following detailed specification in which is described the preferred embodiment of the invention illustrated in the accompanying drawing, in which:

25 Fig. 1 is a perspective view of a preferred form of vanity case incorporating features of the invention.

Fig. 2 is a top plan view thereof partly broken away.

30 Fig. 3 is an end view thereof, partly in section.

Fig. 4 is an enlarged fragmentary sectional view of the latch means as manipulated for opening of the case.

35 Fig. 5 is an exploded perspective view of details of the invention.

Referring to the drawing in greater detail, the case preferably comprises the portions 10 and 11 joined together at one edge as by means of the hinge 12. In the present instance it is preferred 40 to form the case as a flat rectangular unit with the hinge along one of the longer edges, and to position in one of the portions such as 11, means 13 for holding powder and rouge, etc., the other portion 10 of the case being adapted to house and contain a mirror, comb, etc.

45 In the present structure it is preferred to provide the hinge 12 with spring means which at all times tends to swing the portions 10 and 11 of the case relative to each other to open the case.

50 A preferred means of realizing the invention comprises an elongated inflexible latch member 14 of rectangular form positioned along the case edge opposite the hinge 12. While not essentially so, this member is preferably approximately as

long as the length of the case and of a width substantially equal to the thickness of the case.

Fixed to the member 14 by soldering, brazing or the like, there is provided a member 15 reentrantly bent to provide loops or sockets 16 which 5 protrude through the opening 17 in the case portion 11 into the interior of the case.

Within the loops 16 is positioned the central portion of a bar spring 18, slightly bent at each end to impinge at 21 on the inner face of the wall 10 11a of the case portion 11.

In the above manner, the latch member 14 is held in intimate contact with the edge of the case along which it is positioned with its upper inturned edge 14a overstanding the lug 10a on 15 the case portion 10.

The latch member 14 may be provided with an operating knob 19 to facilitate manipulation of said member.

As can be noted from Figures 2 and 3, the bar 20 spring 18 acts to maintain the edge 14a of the latch member 14 in overstanding relation with the lug 10a and, therefore, maintaining the case portions 10 and 11 closed. When the latch member 14 is rocked by manipulation of the operating 25 knob 19, this member will pivot at 20 against the case portion 11 and the bar spring 18 will be straightened somewhat due to the movement of the loops 16 towards the wall 11a of the case portion 11. When freed, the latch member 14 will 30 resume its original position, being so urged by the bar spring 18 which tends to resume its slightly bent condition.

When the latch member 14 is rocked as shown 35 in Figure 4, the spring incorporated with the hinge 12 will immediately cause the case portion 10 to fly open affording ready access to the contents of the compact means 13.

The case is easily closed by merely moving together the free edges of the portions 10 and 11, 40 the lug 10a being formed with a sloping face 10b which cams past the edge 14a, said edge finally snapping over the lug 10a.

As can be seen from the foregoing, simple and economical means for opening and closing a 45 vanity case or the like has been provided in its preferred embodiment. It is also apparent that, though simple, structural changes within the spirit of the invention may be made by skilled persons and, therefore, the scope of the invention as 50 outlined in the following claims should rather be determined by the prior art.

Having thus described my invention, what I 55 claim as new and desire to secure by Letters Patent, is:

1. A vanity case or the like comprising a pair of shallow rectangular case portions, a spring tensioned hinge pivotally connecting said case portions, a latch member mounted along an edge 5 of one of the case portions and opposite said hinge, a lug on the other case portion engageable by said latch member for maintaining said case closed, and resilient means for pivotally mounting said latch member comprising socket means 10 on the latch member protruding into the interior of the case, and a bar spring positioned in the socket means, said bar spring having its ends in contact with the portion of the case mounting the latch means.
- 15 2. A vanity case or the like comprising a pair of shallow rectangular case portions, a spring tensioned hinge pivotally connecting said case portions, a latch member mounted along an edge of one of the case portions and opposite said hinge, a lug on the other case portion engageable by said 20 latch member for maintaining said case closed, and resilient means for pivotally mounting said latch member comprising a bar spring positioned in the socket means, the ends of said spring being in contact with the portion of the case mounting said latch means.
- 5 3. A vanity case or the like comprising a pair of hinged portions, a lug on one of said portions, and a latch member on the other portion for engaging said lug to maintain said case closed, and resilient means for pivotally mounting said latch member comprising a socket means on the latch member protruding into the interior of the case, 10 and a bar spring positioned in the socket means, said bar spring having its ends in contact with the portion of the case mounting the latch means.

FRED SPITALNY. 20
